HYDRAULIC PRESS

John H. Maude, Verdun, Quebec, Canada, assignor to Dominion Engineering Works Limited, Lachine, Quebec, Canada

Application May 13, 1938, Serial No. 207,733

10 Claims. (Cl. 267—1)

This invention relates to hydraulic presses and has particular reference to presses equipped with hydraulic cushioning rams serving to create fluid resistance to oppose the downward movement of the lower work supporting platen during a working stroke of the upper platen and to raise said lower platen to starting position during return of the upper platen. More particularly, the invention relates to improved means for controlling the flow of pressure fluid to and from the pressing and/or cushioning cylinders of the press and is adaptable to various kinds of presses whether designed for manual, semi-automatic, or automatic operation.

A feature of this invention resides in the provision of a pressure control valve between the pressing cylinders and the main reversing valve. This pressure control valve may be set to cause the high pressure fluid to be successively delivered to different pressing cylinders at different stages of the working stroke of the upper platen. The pressure control valve may also be set to selectively vary the number of pressing cylinders to which high pressure fluid is supplied during the pressing operation. This enables the maximum fluid pressure applied to the upper platen during the pressing operation to be conveniently varied within wide limits and is accomplished by a simple adjustment of component parts of the pressure control valve.

Another feature of the invention resides in the provision of a simple and efficient resistance-control assembly for predetermining the fluid resistance opposed to downward movement of the lower platen during the pressing operation. A characteristic feature of this assembly is that the fluid resistance opposing descent of the lower platen during the pressing operation is predetermined by the setting of a loaded pressure relief valve through which pressure fluid, previously supplied to the rams to raise the lower platen to starting position, is discharged to a suitable tank.

Another characteristic feature of the resistance-control assembly is the provision of a selector valve which enables the maximum fluid resistance offered to downward movement of the lower platen to be varied within wide limits for any particular setting of the pressure relief valve.

A further feature of the invention resides in the provision of a fluid pressure control system in which the pressing, push back, and cushioning cylinders of the press are supplied with high pressure fluid from a common source and through the agency of a common reversing valve connected between said source and cylinders.

Other characteristic features and advantages of the invention, as well as the novel details of the particular embodiment selected for illustration will be apparent from the following detailed description taken in connection with the accompanying drawings, in which—

Figure 1 is a diagrammatic view of the component parts of a press showing one embodiment of the present invention.

Figures 2 and 3 are views similar to Figure 1 but showing certain parts in different positions.

Figure 4 is an enlarged vertical sectional view of the pressure control valve which is connected between the pressing cylinders and the main reversing valve as shown in the preceding figures.

Figures 5 and 6 are enlarged detail views showing different operating positions of the selector or isolating valve forming part of the assembly appearing in Figure 4.

Figure 7 is a vertical sectional view of one of the prefill valves associated with the pressing cylinders.

Figure 8 is a diagrammatic view illustrating certain modifications of the fluid supply and exhaust connections to the fluid resistance-control assembly associated with the lower platen.

Figure 9 is a view similar to Figure 8 but showing a further modification in which the fluid resistance-control assembly associated with the lower platen is contained in a hydraulic circuit which is entirely independent of the hydraulic circuit provided in connection with the pressing and push back cylinders of the upper platen.

Figure 10 is a vertical sectional view of the preferred type of pressure control valve provided between the pressing cylinders and the main reversing valve.

Figure 11 is a sectional view showing more or less diagrammatically certain modifications of the fluid resistance control assembly associated with the cushioning rams.

Figure 12 is a sectional view taken substantially along the line 12—12 of Fig. 11. In this view certain parts appearing in Fig. 11 are omitted.

Referring to the diagrammatic illustrations appearing in Figs. 1 to 3 inclusive, the upper press platen and the lower or cushioning platen are respectively indicated at 5 and 6. The upper platen is operated by main central ram 7 working in cylinder 8 and two auxiliary side rams 9 working in cylinders 10. The lower platen is carried by three cushioning rams 11, 12 and 13 working, respectively, in cushioning cylinders 14, 15 and 16.

Platen 5 is equipped with a conventional top drawing tool A. The cooperating bottom tool B

is shown mounted on the bolster plate C. The work D is shown resting on a draw ring E which operates in the space between the tool B and a surrounding guide ring F fastened to plate C. Draw ring E is supported from platen 6 by cushion pins G working in the guide openings H of plate C. During the pressing operation the work D is gripped between tool A and draw ring E and drawn downwardly around the bottom tool B.

Fluid is supplied to the lower ends of cylinders 10 and exhausted therefrom through line 17. This line is connected to port 18 of main control-valve casing 19. It is also connected to ports 20, 21 and 22 of the prefill valve casings 23, 24 and 25 through which fluid passes into and out of 15 the upper ends of cylinders 8 and 10. As herein-after described the prefill valves 26, 27 and 28 are biased to close against the seats 29, 30 and 31.

The cylinder spaces served by line 17 are hereinafter referred to as the push back cylinders to distinguish them from the cylinder spaces above the rams 7 and 9 which are hereinafter termed the pressing cylinders. It is feasible to operate the platen 5 on its return stroke by push back rams which are entirely separate from the pressing rams employed for operating the platen during the working or pressing stroke. Consequently, the terms pressing and push back cylinders as employed in the present description and claims are intended to cover this arrangement as well as the arrangement actually shown in the present drawings.

A port 33 in the upper end of cylinder 8 opens into the lower portion of valve casing 23. Similar ports 34 and 35 in the upper ends of cylinders 10 open into the lower portions of the valve casings 24 and 25.

A port 37, provided in valve casing 23 below valve seat 29, is connected, by line 38, to port 39 provided in casing 40 of an automatic pressure-control check valve 41. Similar ports 42 and 43, provided in valve casings 24 and 25 below valve seats 30 and 31, are connected by line 44 to port 45 of check valve casing 40. With shut-off valve 46 in the open position shown in Figure 1, port 45 is connected through passage 47 and line 48 to port 49 of main control valve casing 19. Communication between port 39 and passage 47 is established, at the proper time, by automatic opening of a pressure operated check valve 51 which remains closed until a definite pressure is established in passage 47. When this occurs the pressure in bypass 52, communicating with passage 47, acts against plunger 53 to open valve 51 so that port 39 is then connected, through passage 47 and line 48, to main valve port 49.

The ends of main control valve casing 19 are provided with exhaust ports 58 and 55a connected to an overhead filling or supply tank 56 by a common return or exhaust pipe 57 provided with a stop valve 58.

Valve casing 19 is also provided with a pressure supply port 19a connected, by pipe 59, to the pressure side of pump 60. The suction side of pump 60 is connected to tank 56 by pipe 61 provided with stop valve 62.

The main control valve 64, operating in valve casing 19, is provided with an annular port 65 and an operating rod 66. The rod 66 may be operated through the agency of the control mechanism disclosed in the co-pending application of William P. Muir and John H. Maude, Serial #241,190, filed Nov. 18, 1938, and now matured 75

into Patent No. 2,246,379, dated June 17, 1941, or in any other suitable manner.

Prefill valve casings 23, 24 and 25 are respectively provided, above the valve seats 29, 30 and 31, with ports 68, 69 and 70. These ports are line-connected to tank 56 as indicated at 71.

The downward or working stroke of platen 5 commences when main control valve 64 is shifted to the position shown in Figures 1 and 2. This permits fluid, previously supplied to the lower ends of cylinders 10, to be forced back, through line 17 and main control-valve ports 18 and 55a, to exhaust line 57 leading to tank 56. As rams 7 and 9 move downwardly the initial suction created in the upper ends of cylinders 8 and 10 is sufficient to immediately open the prefill valves 26, 27 and 28. The cylinder spaces above the descending rams are thus immediately filled by fluid supplied from tank 56 through the line connections 71. At this time fluid also flows from pump 60 into the upper ends of cylinders 10 but not into the upper end of cylinder 8. The flow from pump 60 to cylinders 10 is through line 59; main valve ports 19a, 65 and 49, line 48, passage 47 and port 45 of pressure control relief valve 41, and line 44. Until platen 5 contacts the work there is no pressure in passage 47, bypass 52 and cylinders 10 and 8, so that the pump discharge merely augments the flow. As soon as platen 5 engages the work, the resistance to its downward movement causes an immediate rise of pump pressure in the upper portions of cylinders 10 and in passages 42, 43, 44 and 47, so that prefill valves 27 and 28 are constrained to close immediately on their respective seats 30 and 31.

The preliminary pressing work is performed by the whole of the pump discharge directed into cylinders 10 while cylinder 8 continues to prefill from the overhead tank, so that this light pressing occurs at a rapid rate. As the work resistance increases, the pressure developed by the pump also increases, until it reaches a predetermined amount, when fluid in passage 52 opens valve 51 so that a portion of the pump fluid now flows through line 38 through port 37 to immediately close the prefill valve 26 against its seat 29 and to act against ram 7 in cylinder 8, and provide additional pressure needed for the pressing operation.

When the pressing operation is completed, platen 5 is returned to starting position by shifting main control valve 64 to the position shown in Figure 3. Fluid is now pumped to the lower ends of cylinders 10 through line 59, main valve ports 19a, 65 and 18, and line 17. Fluid, previously supplied to the upper ends of cylinders 8 and 10, is returned directly to tank 56 through the prefill valve connections 71, the prefill valves 26, 27 and 28 being held open by the pressure in line 17 acting against the valve plungers 26a, 27a and 28a.

In this position of valve 64 a portion of the fluid previously supplied to the upper ends of cylinders 10 may be returned to tank 56 through prefill valve ports 42 and 43, line 44, port 45 and passage 47 of valve 41, line 48, ports 49 and 55 of main control valve 19 and line 57. At this time it is immaterial whether valve 51 is open or closed. If it is closed, all the fluid previously supplied to cylinder 8 will be returned directly to tank 56 through port 68 and connections 71. If it is open, a portion of the fluid from cylinder 8 may be returned to tank 56 through port 37,

line 38, passage 47 of valve 41, line 48, ports 49 and 55 of main control valve 19 and line 57.

With reference to the lower platen 6, it will be noted that the lower ends of cushion cylinders 14 and 16 are connected by a common line 75 to port 76 of a cushion or resistance-control valve assembly 77. The remaining cushion cylinder 15 is connected by line 78 to port 79 of valve assembly 77. As shown more particularly in Fig. 4, ports 76 and 78 open into annular valve ports 80 and 81 formed in the wall of a horizontal valve bore 82 provided in valve casing 77a. Bore 82 is also provided with annular valve port 83 located between ports 80 and 81. The two last mentioned valve ports are connected by passages 84 and 85 to opposite ends of a horizontal valve bore 86 located between the lower valve bore 82 and an upper horizontal valve bore 87. A vertical bore 88 intersects bores 87 and 86 and communicates, at its lower end, with the intermediate valve port 83 of bore 82. The upper end of bore 88 is connected to branch 17a (Figs. 1 to 3) of the previously mentioned fluid line 17. A check valve 90 in the upper end of bore 88 is biased by spring 91 to close against a downwardly facing valve seat 92. This check valve opens automatically to admit pressure fluid to bore 88 when pump pressure is established in line 17 during a return stroke of platen 5. When line 17 is connected to exhaust line 57 during a working stroke of platen 5 valve 90 closes under the influence of spring 91 to prevent reverse flow from bore 88 to line 17.

A cylindrical isolating or selector valve 94 is slidably mounted in bore 82. This valve is provided with an external annular port 95 and an internal longitudinal passage 96, the latter being open to bore 82 at opposite ends of the valve. Mechanical shifting of valve 94 to different operating positions, hereinafter referred to, may be accomplished through the agency of any suitable valve shifting mechanism such, for example, as the rack and pinion mechanism generally indicated at 97.

Valve 94 is also provided with a stem 99 extending outwardly through a packing gland 100 closing one end of bore 82. The remaining end of bore 82 is connected to exhaust line 57 as indicated at 82a.

A valve casing 101 is arranged in bore 86 so that it intersects but does not block the lower portion of vertical bore 88. A port 102 at the left hand end of casing 101 opens into the left hand end of bore 86 which, as previously stated, is connected to annular valve port 80 by passage 84. The inner end of port 102 is normally closed by a pressure relief valve 103 which is held to its seat 104 by one end of a valve closing spring 105. A longitudinal port 106 at the right hand end of casing 101 is connected by lateral ports 107, annular port 108 and passage 85 to valve port 81 of bore 82. The inner end of port 106 is normally closed by valve 109 which is opposed to valve 103 and held to its seat by the remaining end of spring 105. In this connection it will be noted that the end portions of spring 105 are seated in sockets extending inwardly from the inner ends of valves 103 and 109. The intermediate portion of casing 101 is provided with lateral ports 112 opening into the vertical bore 88.

Valves 103 and 109 are provided with longitudinally extending circumferentially spaced ribs 113 engaging the circumferential wall of casing 101. These ribs provide intervening flow passages through which fluid is permitted to flow

from end ports 102 and 106 to intermediate ports 112.

The upper valve bore 87 is connected to exhaust line 57 by a passage 115 which serves as a pressure relief passage for the vertical bore 88. Communication between passage 115 and bore 88 is controlled by an adjustable resistance-control valve 116 operating in that portion of bore 87 which lies at the left of vertical bore 88. The right hand end 117 of valve 116 is normally closed against the seat 118 by a spring 119. One end of spring 119 is seated in a socket formed in the left hand end of the valve. The other end of said spring is seated in an opposing socket formed in a threaded plug 120 closing the left hand end of bore 87. The right hand end of valve 116 is provided with a stem 123 extending across the vertical bore 88. The free end of this stem terminates in a cylindrical enlargement 125 working in that portion of bore 87 which lies at the right of vertical bore 88. The cylindrical stem enlargement 125 is provided with a socket accommodating one end of a pressure applying spring 127. The other end of spring 127 bears against the inner end of an adjusting screw 128 which is threaded through a packing gland 129 closing the right hand end of bore 87. An operating wheel 130 is provided at the outer end of screw 128.

The area of the seat engaging portion of valve 116 is slightly greater than the opposing area of the valve stem at the inner end of the enlargement 125. This slight preponderance of pressure areas exposed to the pressure in the vertical bore 88 enables the valve springs 119 and 127 to be made somewhat smaller than would otherwise be feasible. It is preferred that the opposing springs 119 and 127 have different periodicities in order to damp out oscillations. The design and assembly of the component parts of this resistance control valve is preferably such that, with the hand wheel 130 screwed back to give zero pressure in the right hand spring 127, the left hand spring 119 alone gives a valve closing pressure of approximately the maximum desired fluid resistance pressure in the system. By turning the hand wheel in the proper direction compression is applied to spring 127 which, by opposing the valve closing pressure of the main spring 119, reduces the effective spring load on valve 116 to give a reduction in relief. In other words the valve closing pressure of spring 119 may be balanced to any desired extent by increasing the opposing pressure offered by the spring 127.

In describing the functioning of the complete resistance-control valve assembly 77 it will be assumed that platen 5 is making a return stroke with main control valve 64 and valve 94 of the resistance-control assembly 77 positioned as shown in Fig. 3. In this position of valve 94 the three cushion cylinders 14, 15 and 16 are connected through lines 75 and 78 and valve ports 76, 79, 95 and 83 to vertical bore 88 which, in turn, is connected to branch 17a of line 17. Consequently, the opening of check valve 90 by the pump pressure established in line 17 permits fluid to flow from this line to the lower ends of the three cushion cylinders where the fluid acts against the rams 11, 12 and 13 to raise the platen 6.

During the downward or pressing stroke of platen 5, line 17 is connected to exhaust line 57 as previously described. This permits valve 90 to close so that the fluid previously admitted to bore 88 is trapped against return flow to the

line 17. The lower platen 6 and its rams 11, 12 and 13 therefore recede against a predetermined fluid resistance which is regulated by the setting of the main relief valve 116. When this fluid pressure resisting downward movement of the platen 6 exceeds a predetermined value (determined by the effective valve closing spring load on valve 116) it becomes effective to move valve 116 away from its seat 118 (see Fig. 2) thereby placing vertical bore 88 in communication with relief passage 115 and relief line 57. This permits the fluid trapped in the cushion cylinders 14, 15 and 16, lines 75 and 78 and vertical bore 88, to be forced back to the tank 56 through line 57. From the opening of valve 116 to the completion of the downward stroke of platen 6 the fluid resistance opposed to the downward movement of the cushioning rams 11, 12 and 13 remains at an approximately constant value.

Maximum available resistance to downward movement of platen 6 (for any setting of valve 116) is obtained when valve 94 is positioned as shown in Fig. 3 to connect all three of the cushion cylinders to the vertical bore 88. When it is desired to oppose less than the maximum fluid resistance to downward movement of platen 6, this may be accomplished by shifting valve 94 either to the left or to the right from the position shown in Fig. 3. If valve 94 is shifted to the left, as shown in Fig. 5, the central cushioning cylinder 15 is isolated from vertical bore 88 and is connected to exhaust line 57 through the central passage 96 of valve 94. In this position of valve 94 fluid resistance, as controlled by valve 116, is opposed only to the rams 11 and 13 during descent of the platen 6. If valve 94 is shifted to the right, as shown in Fig. 6, the cushioning cylinders 14 and 16 are isolated from vertical bore 88 and connected directly to exhaust line 57 through the left hand end of bore 82. In this case descent of the platen 6 is retarded, through the agency of valve 116, solely by the fluid resistance opposed to the central ram 12.

The operator may accidentally leave valve 94 in an intermediate position in which the left hand end of the valve overlies port 76 and blocks communication between this port and exhaust passage 57 or in another intermediate position in which the right hand end of valve 94 overlies port 79 in such manner as to block communication between this port and the exhaust passage 96 of the valve. In either of these cases undesired intensification of pressure is liable to occur in the cylinder or cylinders which are thus blocked from communication with the exhaust line. The check valves 103 and 109 are provided to prevent this intensification of pressure in the blocked cylinders. If the fluid pressure in central cylinder 15 is being used to resist descent of the lower platen 6 and valve 94 is inadvertently left in a position blocking communication between ports 76 and the exhaust line 57, the pressure developed in cylinders 14 and 16 will act through valve ports 76 and 80, passage 84, and port 102 to open check valve 103. The opening of this valve permits the fluid in cylinders 14 and 16 and line 75 to escape into vertical bore 88 and from thence through the valve-controlled passage 115 into the exhaust line 57. If fluid pressure in cylinders 14 and 16 is being utilized to resist downward movement of platen 6 and valve 94 is inadvertently left in a position blocking communication between line 78 and exhaust passage 96 of valve 94, the resulting intensification of pressure in cylinder 15 is relieved through

line 78, ports 79 and 81, passage 85, check valve 109, port 88, relief valve 116, exhaust passage 115 and exhaust line 57.

By varying the fluid resistance opposing downward movement of platen 6 I am able to provide a variable "vicing grip" around the edges of the work plate C which are gripped between the tool A and the draw ring E. For any setting of resistance control valve 116 the "vicing grip," insofar as it is determined by the fluid resistance opposing downward movement of platen 6, remains substantially constant from the opening of valve 116 to the end of the pressing stroke. The intensity of the "vicing grip" is varied through stepless variation from maximum to minimum by means of the adjustable resistance control valve 116 in conjunction with the positioning of selector valve 94. The maximum "vicing grip" is obtained when the valve is positioned as shown in Figs. 3 and 4 to connect all three cushioning cylinders to exhaust line 57 by way of vertical bore 88 and main relief valve 116. The minimum "vicing grip" is obtained when valve 94 is positioned, as shown in Fig. 6, so that cylinders 14 and 16 are connected directly to exhaust line 57 through the left hand end of bore 82 while the remaining cylinder 15 is connected to said exhaust line by way of vertical bore 88 and relief valve 116. The intermediate "vicing grip" is provided for when valve 94 is positioned, as shown in Fig. 5, so that cylinder 15 is connected directly to exhaust line 57 through exhaust passage 96 of valve 94 while the two remaining cylinders 14 and 16 are connected to said exhaust line by way of vertical bore 88 and the main resistance-control valve 116.

The prefill valves associated with the upper ends of cylinders 8 and 10 are identical so that the following description of valve 25, as shown in detail in Figure 7, will suffice for all three.

40 In this figure port 22, which connects to tank 56, is shown opening into one side of valve casing 25. When valve 28 is moved downwardly away from seat 31, port 22 is connected to port 132 which, in turn, is connected (by suitable piping not shown) to port 35 of the right hand cylinder 10 (Fig. 1). The high pressure port 43 in Fig. 7 is the same as the port 43 shown in Fig. 1. Valve 28 is guided during its opening and closing movements by wings or vanes 28' working in the seat member 31. This valve is also provided with a depending spring casing 133 containing the valve closing spring 136. The upper end of this spring bears against the central portion of the valve while the lower end rests on a movable valve seat 135 working in the lower portion of the spring casing. The valve seat 135 is engaged by the upper end of a spring adjusting screw 134 having its lower end threaded through a gland nut 137 at the lower end of casing 25. Obviously, adjustment of screw 134 serves to regulate the spring load on valve 28. The plunger 28a which opens valve 28 in response to the development of pump pressure in line 17 is normally raised clear of the valve by a spring 138. When pump pressure is established in line 17 plunger 28a is moved downwardly against the resistance of spring 138 and opens valve 28 against the resistance of valve spring 136.

In Fig. 10 I have shown the preferred construction of pressure-control check valve 41. As shown in this figure, valve opening plunger 53 is moved upwardly against the resistance of a spring 140 and is provided with a stem 53a which engages and opens the valve 51 against the resistance of valve closing spring 51a. Valve 51 is provided

with a guide 53b working in a vertical guideway 141. A screw 142 is threadedly engaged in the upper portion of guideway 141 and is provided, at its upper end, with a hand wheel 142a. By turning the hand wheel in the proper direction, screw 142 may be forced downwardly against valve 51 to prevent the latter being lifted from its seat by pressure developed in bypass 52. When valve 51 is held closed by screw 142 no pump pressure is established in cylinder 8 during the pressing stroke of the platen 5. Provision is also made for disrupting communication between the cylinders 10 and the pressure side of pump 60 during the working stroke of platen 5 and connecting the pressure side of said pump only to the cylinder 8. This is accomplished by closing the shut-off valve 46 to disrupt communication between port 45 and passage 47 and backing off the screw 142 to permit valve 51 to open when the required pump pressure is established in passage 47 and bypass 52.

Instead of being connected to line 57, the exhaust outlet 82a of the resistance-control valve assembly 77 may be directly connected to a leakage or sump tank 145 from which fluid is pumped to tank 56 through line 146, pump 147, line 148, intercooler 149 and line 150.

Further possible modifications of the fluid supply and exhaust connections to resistance-control valve assembly 77 are illustrated more or less diagrammatically in Figs. 8 and 9.

As shown by full lines in Fig. 8, intake bore 88 and exhaust connection 82a of resistance-control valve assembly 77 may be respectively connected to branches 57a and 57b of line 57. In this case the fluid in tank 56 is maintained under pressure by means of air pressure supplied through line 56a. In this particular instance the platen 5 is raised during the return stroke of platen 5 by fluid supplied to cylinders 14, 15 and 16 through line 57 and branch 57a. During the pressing stroke of platen 5 this fluid is forced back to line 57 through branch 57b.

According to another modification the exhaust connection 82a of the resistance-control valve assembly 77 may be connected to the sump tank 145. In this case there will be no communication between exhaust connection 82a and exhaust line 57 but the latter will be connected to port 88 as indicated at 57a.

In all the previously described instances the pressing, push back, and cushioning cylinders form part of a single, self-contained hydraulic control circuit. This, however, is not essential since the fluid circuit of the cushion cylinders 14, 15 and 16 may be made entirely independent of the fluid circuit of the pressing and push back cylinders. One example of the latter arrangement is illustrated in Fig. 9. In this case the bore 88 and exhaust connection 82a of the resistance-control valve assembly 77 are respectively connected to branches 155a and 155b of a line 155 leading to a pressure tank 156 which is separate from the tank 56. Air pressure is maintained in tank 156 by means of compressed air supplied through line 157. Pressure in tank 157 may be maintained at a desired value by means of an adjustable relief valve 158 or by other suitable means.

The operation of the circulating system disclosed in Fig. 9 is substantially the same as that described in connection with Fig. 8, except that,

in the former case, the line 57 and tank 56 are replaced by line 155 and separate tank 156.

When the cushion cylinders are supplied from an accumulator tank as in Fig. 9, the resistance-control valve assembly is modified as shown in Figs. 11 and 12. The principal change involved here is the substitution of screw type shut-off valves 160 and 161 for the slide valve 96. Valve 160 is closed against seat 162 when it is desired to disrupt communication between ports 76 and 88. Similarly, valve 161 is closed against seat 163 to close off communication between ports 79 and 88. The location of shut-off valves 160 and 161 between the main relief valve 116 and the auxiliary relief valves 103 and 109 necessitates a slight but unimportant rearrangement of ports 84 and 115. Aside from the substitution of the shut-off valves 160 and 161 for slide valve 96 the arrangement shown in Figs. 11 and 12 is essentially the same as that shown in Fig. 4.

Having thus described my invention, what I claim is:

1. In a hydraulic press, a plurality of cylinders, rams operating in said cylinders and carrying the lower press platen and a resistance-control valve assembly including a main fluid passage connected to the lower ends of said cylinders, a high pressure line through which fluid is delivered through said passage to said cylinders to raise the platen to starting position, a check valve arranged to prevent reverse flow from said main passage to said high pressure line, a pressure relief passage opening into said main passage, a spring loaded pressure regulating valve normally closing off communication between said main passage and said relief passage, said valve opening automatically to provide a relief connection for said cylinders when the cushioning pressure therein rises to a predetermined value during the actual pressing operation, and selector valve means adapted to be selectively positioned to maintain communication between the main fluid passage and all of said cylinders throughout the entire pressing cycle or to disrupt communication between the main fluid passage and one or more of said cylinders while maintaining communication between said main passage and the remaining cylinder or cylinders throughout the entire pressing cycle.
2. In a hydraulic press, a plurality of cylinders, rams operating in said cylinders and carrying the lower press platen and a resistance-control valve assembly including a main fluid passage connected to the lower ends of said cylinders, a high pressure line through which fluid is delivered through said passage to said cylinders to raise the platen to starting position, a check valve arranged to prevent reverse flow from said main passage to said high pressure line, a pressure relief passage opening into said main passage, a spring loaded pressure regulating valve normally closing off communication between said main passage and said relief passage, said valve opening automatically to provide a relief connection for said cylinders when the cushioning pressure therein rises to a predetermined value during the actual pressing operation, and manually controlled selector valve means adapted to be selectively positioned to control the flow of fluid from said main passage to the lower ends of said cylinders, said selector valve means being selectively shiftable to a position maintaining communication between said main passage and all of said cylinders throughout the entire pressing cycle or to a second position isolating one or more

of said cylinders from said main passage while maintaining communication between said main passage and the remaining cylinder or cylinders throughout the pressing cycle and means for placing the cylinders thus isolated in communication with a pressure relief passage.

3. A resistance control valve assembly of the character described comprising a valve casing provided with a main passage, a supply line through which fluid is supplied to said passage, a check valve arranged to prevent reverse flow from said passage to said supply line, selector valve means controlling communication between said passage and a plurality of ports provided in said casing, said selector valve means being operable to disrupt communication between said passage and one or more of said ports while maintaining communication between said passage and the remaining port or ports, a pressure relief passage opening into said main passage at a point between the check valve and the selector valve means and a pressure relief valve controlling the relief of pressure from said main passage by way of said relief passage.

4. A resistance control valve assembly as set forth in claim 3 in which each of said ports is connected to the main passage by an auxiliary pressure relief passage by-passing said selector valve means, said auxiliary passage being controlled by a check valve which opens to permit flow of fluid toward said main passage but closes to prevent reverse flow.

5. A resistance control valve assembly as set forth in claim 3, including means for establishing a pressure relief connection between a pressure relief passage and the port or ports which are cut off or isolated from said main passage by the port closing action of said selector valve means.

6. A resistance control valve assembly of the character described comprising a valve casing provided with a main passage, a supply line through which fluid is supplied to said passage, a check valve arranged to prevent reverse flow from said passage to said supply line, valve means operable to selectively establish and disrupt communication between said passage and a plurality of ports provided in said casing, said selective valve means being operable to close off fluid passages connecting said main passage with one or more of said ports without closing off other passage connections between said main passage and the remaining port or ports, and a pressure regulating valve extending across said main passage at a point between the check valve and the selective valve means, said pressure regulating valve being slidably mounted in a bore intersecting said main passage and being

provided with a seat engaging portion normally engaged with a valve seat in said bore to close off communication between said main passage and a pressure relief passage communicating with said bore, a valve closing spring acting against one end of said pressure regulating valve to hold the same seated against the pressure developed in said main passage until such pressure reaches a predetermined value, a second weaker spring acting against the opposite end of said pressure regulating valve in such manner as to oppose the pressure of the valve closing spring and adjustable means for varying the compression of the weaker spring to thereby regulate the effective spring load imposed on the pressure regulating valve by the valve closing spring.

7. A valve assembly as set forth in claim 6 characterized in that the opposing springs acting against the pressure regulating valve have different periodicities in order to damp out oscillations.

8. In a hydraulic press, a plurality of cushioning cylinders, rams operating in said cylinders and carrying the lower press platen and a resistance control valve assembly comprising a valve casing provided with a main passage, a supply line through which fluid is supplied to said passage, a check valve arranged to prevent reverse flow from said passage to said supply line, selector valve means adapted to be selectively positioned for controlling communication between said passage and a plurality of ports provided in said casing, said selector valve means being selectively positionable to maintain communication between said passage and all of said ports throughout the entire pressing cycle or to disrupt communication between said passage and one or more of said ports throughout the pressing cycle while maintaining communication between said passage and the remaining port or ports, a pressure relief passage opening into said main passage at a point between the check valve and the selector valve means, a pressure relief valve controlling the relief of pressure from said main passage by way of said relief passage and a fluid line connecting each of said cushioning cylinders to one of said ports.

9. A hydraulic press as set forth in claim 8 comprising three cushioning cylinders, two of which are connected to a single one of said ports while a third cylinder is connected to another of said ports.

10. A hydraulic press as set forth in claim 2 in which the last mentioned pressure relief passage communicates with the first mentioned pressure relief passage which opens into the main passage.

JOHN H. MAUDE.
